UNITED STATES PATENT OFFICE.

ERNEST. ROBERT GODWARD, OF CHRISTCHURCH, NEW ZEALAND.

VAPORIZING ATTACHMENT FOR CARBURETORS.

Application filed August 26, 1921. Serial No. 485,757.

To all whom it may concern:

Be it known that I, ERNEST ROBERT GODWARD, a subject of King George V of Great Britain, residing at 140 Hereford Street, Christchurch, in the Dominion of New Zealand, have invented certain new and useful Improvements in Vaporizing Attachments for Carburetors, of which the following is a specification.

16 This invention relates to vaporizers for internal combustion engines.

The object of the invention is to produce a vaporizer whereby the engine is supplied with a uniform dry gaseous mixture.

18 With this object in view I produce a vaporizer having spiral passages, with one or more convolutions, the said passage being designed in a manner whereby the large surfaces of the partitions between the passages are available for the surface evaporation and time element process. The time element (provided by making an element whereby the charge is compelled to travel a sufficiently long route to completely absorb the wet particles) is very important. It is well known that any volatile liquid requires a given time to become a vapour or gas (the time being less with a greater amount of heat and as the charge is drawn into the engine at a high velocity, by making it travel a long route suitably heated, and with great surface area for the wet particles to be spread upon, a decided time element is supplied which deals efficiently with the low grade fuel.

I provide also a heat element in addition to the spirally shaped passages which constitute the surface and time element.

The heat element is so designed that the 40 various fractions of wet fuel absorb heat from it according to the requirements for evaporation of each fraction, the heavier part of the fuel being treated with the higher temperature, and the lighter parts with 45 a lower temperature.

In the drawings accompanying this specification, I have described the apparatus more particularly in connection with vertically arranged spiral passages, but so 50 that the invention may be more clearly understood in its broad sense, views illustrating horizontal spirally constructed passages of different designs are included. They are all related, or characterized by, having 55 the essence of the invention embodied, namely, the time, surface and heat elements.

In the drawings accompanying this specification,

Figure 1 is an end elevation of the vaporizer and connections looking rearward from radiator end.

Figure 2 is a perspective view showing vaporizer, exhaust and part of the inlet and return pipe, with the cover of the return pipe removed.

Figure 3 is a perspective view showing manifold, inlet and return pipe, carburetor side, portion of return pipe being broken away to show distance pieces and method of its communication to the manifold.

Figure 4 is a sectional view of the vaporizer, the scrolled section taken on line "A—A" Figure 6.

Figure 5 is a perspective view of the scroll.

Figure 6 is a plan of the scroll, showing the corrugated metal ribbon which acts as a spacer between the plates top and bottom.

Figure 7 is a perspective view of the hot box.

Figure 8 is a perspective view of the hot plate.

Figures 9 and 11 are views of alternative designs which embody similar features to those contained in the design illustrated in Figure 4.

Figure 10 is a view showing one of the partitions around the inlet pipe as used in the design illustrated in Figure 9.

Figure 12 is a view of one of the partitions around the inlet pipe as used in the design illustrated in Figure 11.

My apparatus consists of a vessel or chamber comprising an outer cover 1, and one or a series of spiral partitions 2, having one or more convolutions or partial convolutions before reaching its maximum diameter 4, providing a spiral or curved passage or passages 3, spaced apart by separator means such as a narrow corrugated metal ribbon 3^a or other suitable formation, top and bottom, said corrugated metal ribbon 3^a or other suitable formation, where located at the bottom of the passages 3, is in engagement with both the partitions 2 and a hot-plate subsequently described, so that it also possesses the function of aiding or increasing the conduction of heat from said hot-plate to the partitions 2; the sum of the area of the entrances or inlets 5, Figure 6, of the said passages 3 correspond approximately to the area of the inlet 6 and return 7

of the apparatus, although I prefer that it be in excess of the latter areas. The sum of the area of the outlet 9 of the spiral passage or passages 3 may approximately correspond in area to the area of the return 7 which communicates with the intake manifold 8, or in another form the spiral partitions 2 in the vessel or chamber are so arranged that the area in the passage 3 may increase from the inlet 5 to the outlet 9, and reduce the speed of the mixture during its progress through the spiral passages 3. These passage outlets 9 discharge the charge into an annular space 10 surrounded by the outer cover 1. The partitions 2 dividing the spiral passage or passages 3 are vertical, and the fuel mixture, after passing through a primary chamber or carburetor 11, and becoming partly atomized, is drawn into the spiral passage 3 by the suction stroke of the engine, whereupon the charge is subjected to a centrifugal action while passing through the curved passages 3; the wet particles contained in the mixture impinging upon the surface of the partitions 2, and being too heavy to remain suspended (or be carried by the air passing through the spiral passages 3) descend the surface of the partitions 2, meeting increased temperature (due to conduction up the partitions from the hot plate and to radiation from hot plate) until gas is formed, in the event of the liquid fuel reaching the extreme lower edge 3^A of the spiral partitions 2, where it comes in contact with a hot plate 12 (which may be dished with the object of causing a further retardation of the heavy particles by the effect of gravity) further vaporization takes place and finally elongated receptacles 12^A projecting from the said hot plate 12 downwardly into a hot box 13 dissipate any of the wet hydro-carbons which may reach this point.

45 The air which carries or conveys the wet particles of the fuel slows up to a degree that the said wet particles which have become deposited upon the partitioned surfaces descend the partitions 2 by gravitation until the said wet particles, meeting with a gradually increasing temperature, are treated in the manner described.

50 These spiral passages 3 are covered by a top plate 14, which forms a joint 14^A with the top edges 2^A of the said partitions 2, so that the charge cannot escape from the top of the spiral passages 3. The hot plate 12 forms a joint with the bottom edges 3^A of the partitions 2, compelling the charge to travel the spiral or curved route as formed by the spiral or curved partitions. The hot plate 12 or base with the cone member 12^B forms the top member of the heating element which comprises what may be termed a hot box 13, into which the hot exhaust gas

is permitted to enter and heat the plate 12, the cone member 12^B, and elongated receptacles 12^A described above, which latter have thus in addition to the function ascribed to them above, that of collecting heat and 70 conducting it to the plate 12 and thence to partitions 2. Instead of exhaust gases other suitable heating means may be introduced and disposed within the said hot box to supply the heat element for the method 75 herein described.

In fitting the vaporizer to a power unit, it is preferably fitted into, and made part of, or placed in close proximity to the exhaust pipe 15. When in proximity as indicated in Figure 4, there is a branch 15^A attached and led to the bottom of the hot box 13, forming communication between the exhaust and the interior of the hot box as at 15^B, where the exhaust gases enter, and heat the under surface of the hot plate 12, and surfaces 12^C of the downwardly projecting elongated receptacles 12^A. Of course, this manner of connecting with the exhaust of a power unit is merely illustrative, and it will be understood that if desired all the hot exhaust gas may be caused to pass through the hot-box 13.

The upper end of the vaporizer is covered by a cap member 16, in the centre of which a joint is made with the return pipe 7, as at 16^A. There are set screws 17 having their heads outside the cap member 16, and their points inside which are brought to bear against the top plate 14, by means of which a joint is formed between the top and bottom edges of the partitions 2, the plate 14, and the hot plate 12 respectively. There are suitable bolt members 18 to retain the vaporizer as a complete unit.

The heating element thus supports the vaporizer and transmits heat to the vaporizing unit. It is obvious that the temperature is higher at the base of the unit where it is in direct contact with the hot plate 12, thus the spiral partitions 2 have a maximum temperature at the base of the vaporizer, and a minimum at the top; then as it is well known that the fractions of the hydro-carbon oil or petrol as used for internal combustion engine fuel have different degrees of volatility, and as the wet particles or heavy wet fuel descends the partition surfaces, they become further broken up by heat transmitted from the heat element, and form a gas which combines with the air current.

The heavier particles which reach the hot plate 12 are carried along the spiral or curved passage in direct contact with the said hot plate 12, and the progress of the heavier particles along the hot plate 12 in the spiral or curved passages is interrupted first by the corrugated metal ribbon 3^B, and the above described receptacles 12^A; the said

curved passage route provides the time element which is essential to complete the vaporization of the heavier wet particles; thus in the described apparatus, only the wet heavy particles which require heat get it to a degree and for the length of time according to the amount that is required to vaporize them; the upper end of the chamber is comparatively cool, and the waste heat from the exhaust is used to the best advantage by supplying the necessary heat to those particles that require it.

The very large plate surface obtained by this design and upon which the mixture spreads itself, assists vaporization, since centrifugal action exerted upon the fuel mixture tends to deposit the wet particles upon such large plate surface, thus exposing the said wet particles to a moving current of air, which tends to accelerate vaporization by spreading such wet particles in a thin film over a large surface whereby the function of the air current in combination with the varying heat obtained by conductivity through the partitions produces complete vaporization.

In another form of the invention (illustrated in Figures 9 and 10) where the spiral partition 2 may be formed as in the manner of a vertical screw thread having two or more turns, there may be one, as shown in Figure 10, or a multiple of these threads, and they may have an increasing pitch so that they provide a gradually increasing area in the passages.

In this form the cover 1 is a cup shaped member, the surface 1^c thereof fitting snugly over the periphery of the threads forming the partitions 2.

The hot box 13 is a cup shaped member, of greater diameter than the cover 1, providing an annular space 13^a for the exhaust gases.

It will be understood that in this form of the invention the charge of fuel is drawn through the inlet pipe 6 to the lower edge 3^a of spiral passages 3, and from thence along the spiral passages 3 to the top thereof, and into the return pipe 7. It is thus apparent that the separation of the wet particles of the charge is effected by centrifugal force, which tends to impinge them against the hot inner surface 1^c of the cover 1. It is obvious that this design embraces the prominent features previously described, i.e., a surface, heat and time element.

Yet another alternative design, illustrated in Figures 11 and 12, comprising a plurality of plates or discs 2, provided with scroll ridged like partitions 2^b, forming scroll threaded passages 3, between the said plates or discs 2 to increase the length of travel of the charge by making said charge circumgyrate said plates or discs one or more times between the inlet 5 of the

spiral passages and the outlet 9 of said passages at the periphery of the discs 2. In this design the charge enters the top, as in Figure 4, but is drawn down directly on to the hot plate 12 as shown in Figure 11, where it follows a scrolled passage 19 formed in the hot plate 12, an equivalent to the receptacle in member 12^c, Figure 4. This scrolled passage 19 is a channel into which the wet particles of fuel flow from the inside to the outer edge in direct contact with the hot plate. A round baffle plate 20 above this hot plate makes the charge travel out over the periphery of said round baffle, and this baffle 20 is held in a position in proximity to the scrolled passage in the hot plate, but a sufficient distance therefrom to allow a free passageway for the evaporated gas. The plates or discs are covered by a top plate 14^b equivalent to the plate 14 illustrated in Figure 4, which forms a joint with a top disc of the stack, the diameter of the said plate being not greater than the diameter of the discs so that the passageway for the charge drawn from the annular space 10 surrounding the disc is not constricted. There are set screws 17 provided, adapted to register with threaded holes in the cap member 16, and screw therein so that the point of the set screw will engage the plate 14^b to impart pressure thereon, and clamp the stack of discs in position between the top plate 14^b and the flat projection 1^b of cover 1. The charge is then drawn into the stack or column of the plates or discs 2, which provide the surface necessary for a complete evaporation of the fuel, and also greatly reduces the temperature of the charge, which is then led to the outlet as shown.

In operation.—The petrol is drawn through from the main supply tank in any approved way, and after passing through the carburetor 11, is led through the inlet pipe 6 to the top of the vaporizer through a hole 18^b in the cap 16 thereof, and jointed up with a plate 14 adapted to cover, and form a joint 14^a, with the top edges 2^a, of the spiral partitions 2. The plate 14 is maintained concentric with the scrolled member, and with the outer cover 1, by means of set screws 17, which serve the dual purpose of keeping the scrolled member rigid in its place and forming the joint 14^a before referred to, with the scrolled member, plate 14, joint and inlet pipe fitted as described. The fuel is drawn downwardly into the core of the vaporizer, thence into the spiral passages 3 where the wet particles are thrown by centrifugal action on the spiral partitions 2 of the passages 3, where they are spread over the surface of the partitions. Here the lighter particles are absorbed into the current, while the heavier wet particles acted upon by gravity de-

scend the heated partitions, and in descending meet with an increasing temperature due to conductivity of heat upward from the bottom ends of the partitions until they reach the maximum temperature at the hot plate 12; thus the downward travel of the wet particles carries the same under the influence of constantly increasing heat whereby they are vaporized as they meet a degree of heat adequate to produce such effect; if any of said wet particles actually reach said hot-plate 12 they are further retarded in their passage by the corrugated metal ribbon 3^b which separates the partitions, thus forming cells which retard any liquid. Any remaining wet particles fall by gravity into the elongated receptacles 12^a provided in the hot plate 12, where they are subjected to the maximum heat and vaporized. The gas thus formed is drawn into the annular space 10 surrounding the maximum diameter 4 of the scrolled member, to the top thereof, and across the space 10^a into the return pipe 7 surrounding the inlet pipe 6, then is drawn through the said return pipe 7 to the engine. The advantage of placing the inlet pipe 6 to the vaporizer, inside the outlet pipe 7 from the vaporizer, is that the incoming charge contained in the pipe 6 being cold, absorbs a certain amount of heat from the gas in the outlet pipe 7, which is thereby robbed of its heat, thus supplying a cool charge to the engine. The corrugated metal ribbon 6^a in the pipe 7 is supplied for the purpose of forming a distance piece to maintain the pipe 6 centrally disposed within the pipe 7; it also acts as heat radiators to facilitate interchange of heat between the incoming and outgoing gas fuel.

What I claim as new and desire to secure by Letters Patent is:—

1. A vaporizer for hydrocarbon fuel mixtures or the like comprising a fuel mixture receiving element having partitions forming curvilinear outlet passages, and a heat transfer means engaging said partitions whereby heat is assisted by conductivity to extend through said partitions and the passages bounded thereby in a direction opposite to the natural gravitation of fuel within said outlet passages.

2. A vaporizer for hydrocarbon fuel mixtures or the like comprising means for receiving the fuel mixture, said receiving means having a curvilinear partitioned passage for prolonging the progress of the fuel mixture therethrough while at the same time gyrating laterally the latter to deposit by centrifugal action the heavier particles of unvaporized fuel on the walls of said passage, and a heat transfer means engaging the walls of said passage whereby heat is assisted by conductivity to extend through said walls in a direction opposite to the

gravitation of unvaporized fuel both on said walls and in the passage, the temperature varying in degrees from a maximum heat at the bottom of said walls and passage to a minimum heat at the top of said walls and passage. 70

3. A vaporizer as characterized in claim 2 having means for delivering the fuel mixture to said receiving means and means for discharging the vaporized fuel mixture 75 from said receiving means, said delivering means and said discharging means being disposed in intimate parallel relation so that heat of the discharged vaporized fuel mixture is exchanged to the incoming fuel 80 mixture flowing to said receiving means.

4. A vaporizer for hydrocarbon fuel mixtures or the like comprising a casing, a transverse partition providing a hot-plate dividing the interior of said casing to provide a heat transfer chamber in the bottom thereof, means for introducing a hot fluid into said heat transfer chamber, a fuel mixture receiving means within said casing having a vertical central receiving passage and a plurality of curvilinear vertical partitions to form a plurality of radiating curved passages leading outwardly from said central receiving passage with their outer ends spaced from the wall of said casing, means closing the top sides of said curved passages, said hot-plate by engagement with the lower ends of said partitions serving to close the lower sides of said curved passages and said central receiving passage, said hot-plate being adapted to transfer heat by conduction upwardly through said partitions, the temperature varying in degrees from a maximum heat at the bottom of said partitions and passages to a minimum heat 105 at the top of the same, means for delivering a fuel mixture into the upper end of said central receiving passage, and means communicating with the upper end of said casing for discharging vaporized fuel therefrom. 110

5. A vaporizer as characterized in claim 4 in which said fuel mixture delivery means and said vaporized fuel discharge means are disposed in intimate parallel relation so that heat of the discharged vaporized fuel is exchanged to the incoming fuel mixture flowing to said receiving means. 115

6. A vaporizer as characterized in claim 4 in which the bottoms of said curved passages of said receiving means are provided with means in mutual engagement with said hot-plate and the bottom portions of said vertical partitions to both aid in conducting heat from the former to the latter and also for retarding the outward flow 120 of any unvaporized fuel which gravitates into direct contact with said hot-plate whereby its discharge from said passages 125 is delayed until it is finally vaporized. 117

7. A vaporizer as characterized in claim 4 in which said hot-plate is provided with a conical member disposed to project upwardly into said central receiving passage of said receiving means.

8. In a vaporizer for hydrocarbon fuel mixtures or the like, means for delivering a fuel mixture into said vaporizer, means for discharging vaporized fuel from said vaporizer, and said fuel mixture delivery means

and said vaporized fuel discharge means being disposed in intimate parallel relation, so that heat of the discharged vaporized fuel mixture is exchanged to the primary fuel mixture entering the vaporizer. 15

In witness whereof I affix my signature.
